UNITED STATES PATENT OFFICE.

RUSSELL E. SARD, OF COLONIE, NEW YORK.

BOTTLE-OPENER.

1,314,905.

Specification of Letters Patent. **Patented Sept. 2, 1919.**

Application filed April 26, 1917, Serial No. 164,763. Renewed February 1, 1919. Serial No. 274,567.

To all whom it may concern:

Be it known that I, RUSSELL E. SARD, residing at Colonie, in the county of Albany and State of New York, have invented a new and useful Bottle-Opener, of which the following is a specification.

My invention relates to a bottle opener which operates by means of a key-shank; and the object of my invention is to so combine means for opening a bottle with the key-shank as to make the shank a mere handle or lever for the purpose of prying off the cap of the bottle.

The drawings illustrate my invention. Figure 1 shows a form of my invention with the tongue B added to the head of a key and projecting outwardly therefrom.

Fig. 2 shows a form of my invention with a tongue C added to the key head and projecting inwardly and toward the bit of the key.

Fig. 3 shows a form of my invention with the head of the key enlarged in the form of an oval ring D' so as to embrace a bottle cover therein and with the sharpened part E acting as the bottle-cap hook or lifter.

The views shown and the description

herein cover some forms of my invention and I am aware it may be constructed in different forms and described in different terms.

My combination has the key handle A acting as lever for the tongue or hook B on the key-bow or key-head D which acts as a fulcrum.

Fig. 1 shows the key-shank A, and the key-bow or head D with the hook B mounted thereon adapted to engage the cap or cover of a bottle. My invention as shown in Fig. 1 operates by the combined action of the shank, key-bow, and hook to remove the cap or cover of a bottle.

What I claim is:

In combination, a key-shank adapted to act as a lever, a key-bow or head adapted to act as a fulcrum, a hook mounted on the key-bow or head adapted to engage the cap or cover of a bottle, and the parts adapted by the combined action of the shank, key-bow, and hook to remove the said cap.

RUSSELL E. SARD.
